UNITED STATES PATENT OFFICE.

JACOB LAWRENCE JACOBS, OF NEW YORK, N. Y.

STAMPING-MACHINE.

1,360,220.

Specification of Letters Patent. Patented Nov. 23, 1920.

Application filed June 3, 1920. Serial No. 386,232.

To all whom it may concern:

Be it known that I, JACOB L. JACOBS, a citizen of the United States, and resident of the city of New York, borough of Manhattan, in the county and State of New York, have invented a new and Improved 5 Stamping-Machine, of which the following is a full, clear, and exact description.

In connection with stamping, and more 10 particularly stamping ribbons, it is well appreciated that it has been customary to utilize what is known as the "gold leaf process," to obtain a definite impression upon the ribbon.

15 The "gold leaf process," as is well known, involves the expenditure of considerable time and material to properly practice the same.

It has often been attempted to apply gold 20 in liquid form (gold ink) to a ribbon, but this has been heretofore unsuccessful in view of the fact that the impression would not last, and was not clear cut.

It will readily be understood, however, 25 that if the use of ink, gold leaf or liquid were practical, that this would be the most desirable mode of applying marks to ribbons in view of the saving of time involved, as well as the reduction of expense and materials utilized.

With this in view, I have constructed a machine, and more particularly a stamping machine, by means of which gold (liquid or ink) may be used in applying marks to ribbons, and which will reproduce the mark 35 in a clear cut impression, which may be subjected to extremely rough usage without detrimental effects.

It is also well understood, that difficulty 40 has been experienced in properly holding a length of ribbon so that a mark applied to the same will be properly placed upon the body of the ribbon with a view of producing work which shall be neat in appearance.

With this latter defect in mind, I have constructed a machine which, in addition to permitting of the utilizing of liquid gold for applying marks to ribbons, shall further 45 incorporate, as a part of its structure, certain means permitting of the proper holding and guiding of a ribbon, whereby to insure

a perfect alinement of the mark placed upon the same.

Reference is had to the attached sheets of 55 drawings as illustrating one practical embodiment of my invention, and in which drawings,—

Figure 1 is a perspective view of a machine constructed in accordance with my invention.

Fig. 2 is an enlarged perspective view of the die utilized in connection therewith.

Fig. 3 is a plan view of the ribbon holder forming a part of my invention, and 65

Figs. 4 and 5 are enlarged sectional views taken along the lines 4—4 and 5—5 of Fig. 3 respectively.

In these views the reference numeral 10 indicates the bed plate, to which a standard 70 11 is secured, said standard supporting a machine, conforming in its major aspects to the conventional hand printing press in that spring pressed inking rollers 12 are caused to travel over guide rails 13 by means 75 of a handle 14, such rollers traveling over the turn table 15 forming the ink bed at their upper limit of motion, and passing over and applying ink to the die upon moving to their most retracted position. 80

The conventional platen 16 cooperates with the die, and when the rollers 12 have been moved upwardly by means of the handle, the platen in the usual manner is moved forward so as to contact with the die. 85

Referring now more particularly to the die resting in the bed of the press it will be seen that the same conveniently includes a conventional frame 17 in which the die 18 is positioned and held by means of any suitable securing means such as wedges and blocks 19. Contrary to the usual conventional construction heating members formed by rheostat strips 20 are introduced between the side walls of the die 18 and the blocks 95 19, such rheostat including an incasing member and a conventional resistance wire, to the ends of which terminals 21 are connected.

A source of current connects with the 100 wire 22, the end portions of which are connected to the terminals 21 so that the strips 20 are in series. By this arrangement it will be appreciated that the die 18 will be

heated to a high temperature, and that the same may be removed and substituted for any die, by loosening the wedges 19.

Referring now to the platen 16, it will be seen that when the ribbon 23 upon which an imprint is to be made is fed across the face of the same at a position in line with the die 18, that the platen is brought flush against the face of the latter.

Now with a view of providing means which will properly guide and retain the ribbon during the working stroke of the machine, a pair of strips 24 lie across the face of the platen, and have their outer ends hingedly secured as at 25 to the upper edge of the platen 16. The inner ends of the strips 24 extend to a point beyond the lower edge of the platen 16, and are bent, as has been indicated by the reference numeral 26, the springs 27 extending between the ends 26 of the strips 24 and the bed 10 of the machine, any suitable adjusting means such as bolts 28 being provided for regulating the tension of the springs.

It will now be understood, that the ribbon 23 lying across the face of the platen upon the striking surface 29 secured to the same will be normally permitted to move freely with respect to the platen by virtue of the fact that the springs 27 are adjusted with such nicety as to insure the taking up of all of the tension prior to the platen reaching its extreme outer position, so that the springs will act as a buffer to rock the outer ends of the strips away from the face of the platen. However, upon the platen swinging upwardly *i. e.* moving to a point at which the striking surface 29 bears against the face of the die 18, the strips 24 will swing flush against the upper face of the platen, whereby to clamp the ribbon in position. This action will be accomplished by virtue of the fact that one end of the strips 24 is secured to an immovable portion of the machine, to wit, the plate 10; a yielding connection being furnished between these portions by virtue of the springs 27.

The guiding means conveniently embraces a plate 30 formed with a slot 31 through which the ribbon 23 passes, the same being subsequently introduced into the adjustable guiding members 32, whence it passes across the striking surface 29, and under the strips 24 arranged to each side of the same, subsequently emerging through a second pair of adjustable guide members 32, and a receiving platform 33.

In operation it will now be understood, that it will only be necessary to apply liquid gold or ink to the turn table 15 formed in the inking bed, and to apply the die to the bed of the press, current being introduced into the rheostat strips 20 to insure a high heating of the die 18. The ribbon 23 will now be passed through the slot 31

and the adjustable guide members 32 will be opened to permit of the insertion of the ribbon between their bodies and the upper face of the platen 16, the ribbon thence passing under the strips 24 and over the striking surface 29 and so on to the platform 33.

A movement on the part of the handle will now cause the platen to bear against the die, the inking rollers 12 in the usual manner passing upwardly on to the inking bed. A retrograde movement on the part of the handle will open the press and permit an application of ink to the die 18, by means of the inking rollers 12. It will be noted that as the platen moves upwardly the ribbon is held from movement by virtue of the strips 24 which clamp the said ribbon between their under faces, and the upper face of the platen, thus preventing any movement and accordingly blurred marking on the part of the ribbon.

It will also be understood that by virtue of this arrangement that the ribbon may be left in one position, and be applied to the die a number of times without fear of blurred marking in the event that one impression does not give the desired result. Also by reason of the guide members, the ribbon will at all times be properly fed over the striking surface 29 so that the impression upon the ribbon will be properly placed.

Obviously numerous modifications of structure might be resorted to without in the least departing from the scope of my claims, which read as follows.

What I claim as new is:—

1. A stamping machine, including a bed, a die within said bed, a platen, means for moving said platen into and out of contact with said die, means upon said platen for guiding a ribbon across its face, and means for clamping said ribbon against movement with respect to said platen, upon said platen being moved toward said die.

2. A stamping machine, including a bed, a die within said bed, a platen, means for moving said platen into and out of contact with said die, means upon said platen for guiding a ribbon across its face, and means for clamping the ribbon with respect to said platen when the same is moving to that position in which it contacts with the die, said clamping means including a pair of strips hingedly secured at one of their ends to the face of said platen, said ribbon passing under said strips, and means for moving the opposite ends of said strips toward the face of said platen.

3. A stamping machine, including a bed, a die within said bed, a platen adapted to be moved in and out of contact with said die, a pair of strips extending across the upper face of said platen, one of the ends

of each of the strips being hingedly secured to said platen, the opposite ends of said strips being bent, and springs extending between said bent ends, and an immovable portion of said machine.

4. A stamping machine, including a bed, a die within said bed, a platen movable into and out of contact with said die, a pair of strips having one of their ends hingedly secured to said platen, and springs having one of their faces secured to the opposite ends of said strips, said springs being so arranged as to move said strips out of contact with the upper surface of said platen upon the same moving to its extreme position away from said die, and moving said strips in to contact with said platen upon the platen being moved toward said die.

5. A stamping machine including a bed, a die within said bed, a platen movable to and away from said die, guide members se-

cured to said platen, a plate formed with a slot adjacent to one of said guide members, and a receiving plate formed adjacent the second of said members at the side edge of 25 the platen.

6. A stamping machine, including a platen, means for holding a ribbon upon said platen, a frame, a die, wedge members for removably retaining said die within said frame, and means interposed between said die and wedge members for heating said die.

7. A stamping machine including a platen, means for holding a ribbon upon said platen, said stamping machine further including a bed, a die, means engaging said die and bed for removably holding the former within the latter, and heating means interposed between said die and holding means for heating the die.

JACOB LAWRENCE JACOBS.
